United States Patent Office

Des. 204,567
Patented Apr. 26, 1966

204,567

PAIR OF SUNGLASSES OR THE LIKE

Atherton R. Mitchell, P.O. Box 27, Dillon Beach, Calif.

Filed Oct. 11, 1965, Ser. No. 87,412

Term of patent 14 years

(Cl. D57—1)

FIG. 5

FIG. 4

FIG. 1

FIG. 2

FIG. 3

FIG. 1 is a top plan view of a pair of sunglasses, showing my new design showing the visor member in a patterned texture differing from the remainder of the frame.

FIG. 2 is a front elevational view thereof.

FIG. 3 is a side elevational view thereof.

FIG. 4 is a perspective view thereof with the glasses turned 180° from the position illustrated in FIG. 1.

FIG. 5 is a perspective view thereof.

I claim:

The ornamental design for a pair of sunglasses or the like, as shown.
